FREQUENCY-SHIFT KEYING

Lawrence H. Bannister, Hanover, Edward E. Dinowitz, Needham Heights, and Donald M. Powers, Weston, Mass., assignors to Laboratory for Electronics, Inc., Boston, Mass., a corporation of Delaware

Application May 3, 1955, Serial No. 505,704

19 Claims. (Cl. 178—66)

The present invention relates in general to signalling systems and in particular to a novel system providing a plurality of frequency-shifted sub-carriers with limit frequencies controlled by a single crystal and receivable substantially free from unwanted amplitude modulation.

Fundamentally, a frequency-shift keying system, commonly known as FSK, transmits information by selecting for emission one of two limit frequencies, one of which may be called the "mark" frequency, and the other of which may be called the "space" frequency. One method of obtaining this shift is by varying the frequency of an oscillator from one limit frequency to the other. In normal radio-Teletype applications where only a single carrier is being keyed, this method is found satisfactory. However, when a number of sub-carriers are each to be keyed between two limit frequencies, and the "mark" frequency of one sub-carrier is close to the "space" frequency of another sub-carrier, the problem of frequency stability arises because it is necessary to maintain these limit frequencies very close to their nominal values. Thus it became desirable to use an alternate method of keying; namely, switching between two crystal-controlled limit frequencies.

However, this technique introduces another problem. To separate the various closely spaced sub-carriers, the receiver must include filters having very narrow pass bands. When a signal in the pass band is applied suddenly to the input of a filter, there is an exponential build-up of the signal at the output. Similarly, when a signal is removed suddenly from the input of a filter, the output signal decays exponentially. Since the filter is a linear element, these effects are summed; hence, when switching from a "mark" to a "space" frequency, there is a decay of the "mark" frequency and a build-up of the "space" frequency. If the two frequencies are of equal amplitude and are in phase at the time of switching, there is only a slight ripple in the output of the filter. However, if they are not in phase, there is a distinct amplitude dip, or amplitude modulation. In a system utilizing amplitude modulation for transmission of additional information, this dip would be intolerable.

Consequently, it is a primary object of this invention to provide a multi-channel frequency-shift keying system utilizing a plurality of stable sub-carrier limit frequencies switched in a manner which avoids unwanted amplitude response in the receiver.

Another object is to provide apparatus in which pertinent information is transmitted by combining amplitude modulation and frequency shift keying of a plurality of stable carrier signals.

If it were necessary to use a separate crystal or other frequency stabilizing element for each limit frequency as in prior systems, the complexity and expense of utilizing a plurality of sub-carriers would be prohibitive. In accordance with the concepts of this invention, however, a plurality of subcarrier limit frequencies and a timing

2

frequency are all derived from a single stabilized frequency source.

Other objects and advantages of this invention will become apparent from the following specification with reference to the accompanying drawings in which:

Fig. 1 is a graphical display of the effects in the receiver filter output with two limit frequencies out of phase at the time of switching;

Fig. 2 is a graphical picture of the effects in the receiver filter output with two limit frequencies in phase at the time of switching;

Fig. 3 is a block diagram of a preferred embodiment of the invention;

Fig. 4 is a schematic circuit diagram of portions of the block diagram of Fig. 3;

Fig. 5 is a graphical presentation of a 500 c.p.s. square wave signal and a 100 c.p.s. timing frequency signal plotted to a common time scale;

Fig. 6 is a more detailed block diagram of the count-down chain disclosed in Fig. 3;

Fig. 7 is a schematic circuit diagram of the bistable multivibrator disclosed in Fig. 6; and

Fig. 8 is a graphical presentation of the output waveform of the mixing bridge shown in Fig. 4.

With reference now to the drawing, the nature of the problem will become apparent from examination of Fig. 1 where the signal output of a high Q filter is shown, assuming the filter had been energized by a constant amplitude signal of frequency f_1 long prior to a time t_s , at which point the signal is suddenly removed. The portion of the waveform after t_s illustrates the normal exponential decay. Also shown in Fig. 1 is the output of the same filter, assuming it has been energized at t_s by a constant amplitude signal of frequency f_2 , illustrating the normal exponential rise. It will be observed that the signals at frequency f_1 and f_2 are in exactly opposite phase at time t_s . As a practical matter, when switching from one limit frequency signal to the other, the output of a filter of an FSK receiver is the sum of two signals similar to those described above. From a linear addition of both signals, also shown in Fig. 1, it is seen that shortly after the instance of switching, a relatively marked amplitude fluctuation (or amplitude modulation) occurs in the region between the two constant amplitude time intervals. Thus, if this summation signal were to be used for the transmission of intelligence to a remote receiver, the amplitude transient might seriously impair the significance of the communication.

Fig. 2 illustrates the effect of a similar phenomenon, with the exception that at time t_s the signals at frequency f_1 and f_2 are precisely in phase. It is evident from examination of the summation signal that under these circumstances, there is substantially no amplitude modulation introduced in the resultant signal. Having discovered the phase relation between the signals which virtually eliminates the unwanted amplitude modulation, it is appropriate to consider methods and apparatus for practicing the invention.

Broadly speaking, the present invention provides, as an output from each information channel, a signal which is switched between two fixed frequency limits, the difference between which is some integral multiple of a timing frequency. The phase of the difference frequency signal obtained by mixing the two limit frequency signals is compared with the phase of the timing frequency signal and a signal indicative of any phase difference between these is made to adjust the phase of one or both limit frequency signals until the phase difference between the difference frequency signal and the timing frequency signal is a predetermined value. The switching of a channel output from one limit frequency to the other is synchronized with the timing signal so that the switching occurs only when

the two limit frequency signals are substantially in phase. The timing signal is preferably a square wave.

With reference now to Fig. 3, there is shown the block diagram of a preferred embodiment of the invention. The frequency from crystal oscillator 11 is divided in a count-down chain 12 to provide a plurality of signal frequencies which are integral quotients of the oscillator frequency, one of which is used as a timing frequency. The remaining quotient signals are combined in mixers like mixers 13 to provide a plurality of pairs of limit frequency signals such that the difference between the limit frequencies of a pair is some integral multiple of the timing frequency. The amplitudes of the limit frequency signals are regulated by AGC circuits 16 to be of the same predetermined value. Hereafter, the discussion will be limited to one pair of limit frequency signals, f_1 and f_2 , it being understood that the other channels are operative in the same manner. The two limit frequency signals are combined in mixer 17 after filtering by filters 14 and 15, providing a difference frequency output $f_2 - f_1$ whose phase is compared in phase detector 18 with the timing frequency signal, or one of its harmonics, from output 21 of the count-down chain 12. The output of phase detector 18 is applied to the phase-control input of filter 15, varying the phase of f_2 until $f_2 - f_1$ is substantially in phase quadrature with the fundamental component of the square wave timing signal. This condition requires f_1 and f_2 to have the same phase at the switching time. The limit frequency signals f_1 and f_2 are applied subsequently to switch 19. The timing signal is applied to coder 22 which encodes the information input into a pulsed output synchronized with the timing signal. The pulsed output is applied to switch 19, switching output 23 between outputs 24 and 25 only when f_1 and the phase-corrected f_2 are substantially in phase. The resulting message provided by output 23 may be amplitude modulated with additional information and when applied to a receiver filter, it will provide no undesired amplitude modulation at the output.

The foregoing discussion of Fig. 3 should facilitate the understanding of Fig. 4 wherein the schematic circuit diagram of filters 14 and 15, AGC circuits 16, mixer 17, phase detector 18, and switch 19 are shown. Wherever applicable, the reference numerals of Fig. 3 are carried over in Fig. 4.

With reference now to Fig. 4, two signals, respectively having a component at the frequency of limit signals, f_1 and f_2 , enter at terminals 26 and 27 respectively. Since filters 14 and 15 are substantially identical in operation with the exception that filter 15 has the phase control, only filter 15 will be described in detail.

Tube V1 and its associated components comprise a sharply tuned amplifier with resonant circuits 31 and 32 tuned substantially to f_2 . Resistors 33 and 34 are chosen in accordance with the bandwidth desired for a particular filter. Tube V2 serves as a variable reactance element across tuned circuit 32, causing the resonant frequency thereof to vary about f_2 with a corresponding phase-shift variation at frequency f_2 . The output voltage of phase detector 18 applied to the grid of reactance tube V2 controls this phase shift to be such that the maximum amplitude of the difference frequency signal $f_2 - f_1$ occurs at a time coincident with an edge of the square wave timing signal. This will be discussed in detail when the operation of phase detector 18 is explained.

The signal of frequency f_2 across tuned circuit 32 is amplified by V3 and thence applied to the grid of cathode-follower V4. The output of cathode follower V4 is applied to one grid 35 of the mixer V5 by capacitor 37 and resistor 36 for mixing with the signal of frequency f_1 from filter 14, the latter being applied to the grid 38 of V5. The signal on the plate of V5 includes the 100 c.p.s. difference frequency, $f_2 - f_1$. The high fre-

quency signals are bypassed largely by capacitor 41 and the 100 c.p.s. difference frequency is applied to point X of the diode bridge 42 comprising V6, V7, V8 and V9 through resistor-capacitor coupling network 43.

The square-wave timing signal, of frequency chosen to be 100 c.p.s. in this embodiment, is applied symmetrically from input terminals 44 to bridge 42 through resistor-capacitor coupling networks 46 and is used as a bridge switching signal. Fig. 8 is the waveform on point 10 X of the bridge 42 resulting from the mixing of the square wave timing frequency signal and the 100 c.p.s. sinusoidal difference-frequency signal from the plate of mixer tube V5. The angle ϕ is a measure of the difference between the time the sinusoidal waveform reaches its maximum and the square wave polarity changes. In radian measure ϕ is

$$2\pi \frac{t}{T}$$

20 radians where t is this time difference and T is the period of the 100 c.p.s. signal.

The D.-C. component, E_{dc} , is represented by the dotted time axis and represents a voltage value such that the area between the axis and the portion of the waveform thereabove is just equal to the area between the axis and portion of the waveform therebelow. The amplitude of the sinusoidal waveform is designated as A. It may be shown that:

$$E_{dc} = \frac{2A \sin \phi}{\pi}$$

Hence, there is no D.-C. component when the maximum amplitude of the sinusoidal waveform coincides with an edge of the square wave. The maximum amplitude of the difference-frequency waveform corresponds to an instant in time when f_1 and f_2 are in phase. By switching from one frequency to the other at one defined edge of the timing frequency signal the transient free switching described above is attained. The defined edge of 40 the timing frequency signal will be considered below in the discussion of Figs. 5 and 6. Accordingly, the D.-C. component of the waveform at point X appears at the output of low-pass filter 45 and is applied to the grid of reactance tube V2 as a control voltage. The phase of the signal of limit frequency f_2 is controlled thereby to maintain point X at substantially zero D.-C. potential.

The phase control described above, which will correct for errors of $\pm 90^\circ$ is adequate when all the frequencies to be mixed are derived from the reference source of fixed frequency by dividing repeatedly by two. However, additional phase correction is required when some of the mixing signal frequencies are odd multiples of the timing frequency.

With reference now to Fig. 5, there is shown the 100 c.p.s. square wave timing signal plotted graphically to the same time scale as the 500 c.p.s. square wave available from count-down chain 12 in this embodiment. It was stated above that the switching between limit frequency signals occurred in synchronism with a defined edge of the timing signal. The defined edge of the square wave timing signal corresponds to an instant in time when the output at terminal F of multivibrator 67 of Fig. 6 suddenly changes to a less positive potential. The waveform plotted in Fig. 5a is that which appears on the aforementioned terminal while that of Fig. 5b appears on terminal F of multivibrator 73 in Fig. 6. The terminals discussed above will be described in the discussion below of Fig. 6 and Fig. 7. If the 500 c.p.s. square wave shown in Fig. 5b goes positive when the timing signal goes negative, then without phase control a limit frequency signal which uses the 500 c.p.s. signal in its derivation may be more than 90° out of phase with the limit frequency signal sharing 75 its channel. In such a case, application of a phase con-

tral voltage from phase detector 18 will fail to make the phase difference between the two limit signals zero at the appropriate time.

At time t_0 , it is apparent that the 500 c.p.s. signal is positive going when the 100 c.p.s. signal is negative going. When this occurs, the 500 c.p.s. signal is caused to change again almost immediately thereafter. This very short time interval is indicated at Δt in Fig. 5. Thereafter, when the 100 c.p.s. signal goes negative, so does the 500 c.p.s. signal as illustrated at time t_1 . The means for accomplishing this is described below.

With reference now to Fig. 6, there is shown a detailed block diagram of count-down chain 12. The explanation of this diagram will clearly show the means by which the additional phase control discussed above is accomplished.

The schematic circuit diagram of a conventional bi-stable multivibrator used in the squares of Fig. 6 is shown in Fig. 7 to facilitate the understanding of Fig. 6. However, since the operation of this circuit is well known, it will not be described in detail. It should suffice to say that trigger pulses of appropriate polarity are applied to either input terminal C, D, G, or combinations thereof, depending on the particular application of the circuit. Output signals are available at either or both of terminals E and F, again dependent on the particular application.

In the discussion which follows a specific value of oscillator frequency divided a specific number of times is mentioned for illustrative purposes only. Any frequency may be divided any number of times without departing from the teachings disclosed herein.

Returning to Fig. 6, the 128 kc. signal from crystal oscillator 11 is divided 16 times by multivibrators 51 through 54. The 8 kc. square wave at output F of multivibrator 54 is used to trigger quinary counter 55 and multivibrator 56. Ordinarily, multivibrators 57, 61 and 62 would store eight pulses before providing an output pulse. By utilizing the output of multivibrator 63 to reset multivibrators 57 and 61 to a count of three instead of zero, the four multivibrators in combination provide one negative going pulse for every five negative going input pulses. Multivibrator 63 provides negative going pulses from its E output, $\frac{1}{16000}$ second after multivibrator 54 provides a pulse at its F output terminal because the C input of multivibrator 63 is triggered by the E output of multivibrator 54. This prevents multivibrators 57 and 61 from receiving two trigger pulses simultaneously.

The 1600 c.p.s. square wave from multivibrator 62 is divided by multivibrator 64 to provide an 800 c.p.s. square wave. The 800 c.p.s. signal is divided 8 times by cascaded multivibrators 65, 66, and 67, providing the 100 c.p.s. timing signal at terminals E and F of multivibrator 67.

Meanwhile, multivibrators 56, 71 and 72 functioning as dividers provide a like square wave output at terminals E and F of multivibrator 72. Further division by multivibrator 73 provides 500 c.p.s. square waves at its E and F output terminals.

The multivibrator 74 is triggered by the negative going edges of the timing frequency square wave at terminal F of multivibrator 67. However, a negative going edge does not appear at terminal E of multivibrator 74 until input C thereof is energized by a negative going edge from terminal E of multivibrator 54. The negative going edge from terminals E of multivibrator 74 is applied to terminals G of multivibrators 56, 71, 72, and 73 at a time $\frac{1}{16000}$ second after their being triggered at terminals C and D. This prevents two trigger pulses from being applied to a particular multivibrator simultaneously. These negative going pulses on a terminal G actuate only a multivibrator where the preceding polarity shift in the output waveform on terminal F was positive going. This maintains the desired phase relations described above.

Continuing with the discussion of Fig. 4, the signals of limit frequencies f_1 and f_2 from cathode followers V6 and V4 respectively are coupled to the grids of the switching tubes V10 and V11 respectively. Resistors 47 provide isolation between the source of switching voltage applied at terminals A and B and the sources of limit frequency signals.

The gating signals applied at A and B are identical in waveform but opposite in polarity. This signal is applied from coder 22 and simultaneously causes one of the switching tubes to cut off while causing the other to conduct. The gating signals from coder 22 are synchronized with the timing signal so that they simultaneously shift from one polarity to the other in synchronism with the defined edge of the square-wave timing signal. The output terminal O is switched thereby from one limit frequency signal to the other only when the two signals are simultaneously in phase. The low pass filter 48 prevents any high frequency transients resulting from the switching operation from reaching terminal O. The output at terminal O is then a constant amplitude waveform of the type shown in Fig. 2.

The coder 22 which provides the gating waveform may select either limit frequency of a channel for any time interval that is an integral multiple of the timing signal period. It makes no difference whether the limit frequencies represent the "mark" and "space" of a radio Teletype system or the "zero" and "one" of a coded binary number information system.

By adding another phase-correction loop to control the phase change introduced by the filter 14 the range over which the described phase control system operates can be increased. This permits higher Q resonant circuits to be used which in turn provides better filtering when unwanted modulation products in the output of a mixer are relatively close to a desired limit frequency.

The above system provides a plurality of channels with dual crystal-controlled limited frequencies and a crystal-controlled timing frequency, all derived from and controlled by a single crystal. By this novel method of selecting the switching time, the receiver selective filters provide an output free from undesired amplitude transients.

It is apparent that one skilled in the art may now make numerous modifications of the particular apparatus described herein without departing from the spirit of the material disclosed herein and so the invention is to be construed as limited only by the spirit and scope of the appended claims.

What is claimed is:

50 1. Frequency shift keying apparatus comprising a source of a timing frequency signal and two fixed frequency signals separated in frequency by an integral multiple of said timing frequency whereby said fixed frequency signals are substantially in phase at times separated by the period of said timing frequency signal and means responsive to said timing frequency signal for switching between said fixed frequency signals only when they are substantially in phase.

60 2. In a frequency shift keying system apparatus comprising a source of a timing frequency signal and two fixed frequency signals each frequency thereof and the difference therebetween being integral multiples of said timing frequency, and means responsive to said timing frequency signal for providing one of said fixed frequency signals as an output signal which is changed to the other only when both signals are substantially in phase.

65 3. Frequency shift keying apparatus comprising a source of a timing frequency signal and two fixed frequency signals separated in frequency by said timing frequency whereby said fixed frequency signals are substantially in phase at times separated by the period of said timing frequency signal and means responsive to said timing frequency signal for switching between said

fixed frequency signals only when they are substantially in phase.

4. Frequency shift keying apparatus comprising a source of a timing frequency signal and two equal amplitude fixed frequency signals separated in frequency by said timing frequency whereby said fixed frequency signals are substantially in phase at times separated by the period of said timing frequency signal and means responsive to said timing frequency signal for switching between said fixed frequency signals only when they are substantially in phase.

5. In a frequency shift keying system apparatus comprising a source of a timing frequency signal and two fixed frequency signals each frequency thereof harmonically related to and separated by said timing frequency whereby said fixed frequency signals are substantially in phase at times separated by the period of said timing frequency signal, and means responsive to said timing frequency signal for providing one of said fixed frequency signals as an output signal which is changed to the other only when both are substantially in phase.

6. In a frequency shift keying system apparatus comprising a source of a timing frequency signal and two equal amplitude fixed frequency signals each frequency thereof harmonically related to and separated by said timing frequency whereby said fixed frequency signals are substantially in phase at times separated by the period of said timing frequency signal, and means responsive to said timing frequency signal for providing one of said fixed frequency signals as an output signal which is changed to the other only when both are substantially in phase.

7. Frequency shift keying apparatus comprising, a source of a timing frequency signal and two fixed frequency signals separated in frequency by said timing frequency, a mixer for combining said fixed frequency signals to provide a difference frequency signal, a phase comparator which provides a phasing signal by comparing said timing signal and said difference frequency signal, means for controlling the phase difference between said fixed frequency signals with said phasing signal to be substantially zero coincident with periodic selected alternate polarity reversals of said timing signal, and selective switching means for providing only one of said fixed frequency signals as an output signal which is changed to the other only coincident with a selected polarity reversal.

8. Frequency shift keying apparatus comprising, a source of a timing frequency signal and two equal amplitude fixed frequency signals separated in frequency by said timing frequency, a mixer for combining said fixed frequency signals to provide a difference frequency signal, a phase comparator which provides a phasing signal by comparing said timing signal and said difference frequency signal, means for controlling the phase difference between said fixed frequency signals with said phasing signal to be substantially zero coincident with periodic selected alternate polarity reversals of said timing signal, and selective switching means for providing only one of said fixed frequency signals as an output signal which is changed to the other only coincident with a selected polarity reversal.

9. In a frequency shift keying system apparatus comprising, a source of a timing frequency signal and a pair of equal amplitude fixed frequency signals each frequency thereof harmonically related to and separated by said timing frequency, a mixer for combining said fixed frequency signals to provide a difference frequency signal, a phase comparator which provides a phasing signal by comparing the phase of said timing signal with that of said difference frequency signal, means for controlling the phase difference between said fixed frequency signals with said phasing signal to be substantially zero coincident with periodic selected alternate polarity reversals of said timing signal, and selective switching means which

selects one of said fixed frequency signals as an output signal which is changed to the other only coincident with a selected polarity reversal.

10. In a multi-channel frequency-shift keying system apparatus comprising a source of a fixed frequency signal, means for deriving therefrom a timing signal and a plurality of pairs of limit frequency signals, means for selectively providing one of said limit frequency signals from each pair as an output signal, and means responsive to said timing signal for changing the output signal from a pair to the other limit frequency only when the limit frequencies of said pair are substantially in phase.

11. Frequency-shift keying apparatus comprising, a source of first and second fixed frequency signals, means for controlling the amplitude of said fixed frequency signals to be a predetermined value, a source of a timing signal of frequency which is the difference between said first and second fixed frequencies, means for mixing said first and second fixed frequency signals to provide a difference frequency signal, a phase detector energized by said timing signal and said difference frequency signal which provides an output for controlling the phase of said second fixed frequency signal to maintain a predetermined phase relation between said difference frequency signal and said timing signal, and switching means operative in synchronism with said timing signal for providing one of said fixed frequency signals as an output signal and changing to the other only when both are substantially in phase.

12. Multi-channel frequency-shift keying apparatus comprising, a source of a fixed frequency signal, means for integrally dividing said fixed frequency signal to provide a plurality of quotient signals and one timing signal of a predetermined frequency, means for mixing said quotient signals to provide a plurality of pairs of first and second limit frequency signals whose frequency difference equals the frequency of said timing signal, means for controlling the amplitude of said limit frequency signals to be a predetermined value, means for mixing said first and second limit frequency signals of a pair to provide a difference frequency signal, a phase detector for each pair which provides an output for controlling the phase of said second limit frequency to maintain a predetermined phase relation between said timing signal and said difference frequency signal, switching means associated with each pair operative in synchronism with said timing signal for selectively providing one of said limit frequency signals in each pair as an output signal and changing to the other only when both are substantially in phase.

13. In a multi-channel frequency shift keying system apparatus for each channel comprising, a pair of mixers, a source of fixed frequency signals, a source of a timing signal, each mixer energized by at least two of said fixed frequency signals, a pair of filters, each with a phase control input and an amplitude control input, the one filter energized by the one mixer, the other filter energized by the other mixer, a source of an amplitude reference signal, an automatic gain control circuit associated with each filter for comparing the output signal of each filter with said amplitude reference signal to provide an amplitude control signal, the amplitude control input of each filter energized by said amplitude control signal provided by the associated automatic gain control circuit, means for combining the output signals of each filter to provide a difference frequency signal whose frequency equals that of said timing signal, a phase detector associated with each filter for providing as an output a phase control signal indicative of the phase difference between said difference frequency signal and said timing signal, means for applying said phase control signal to the phase control input of the associated filter, and switching means responsive to said timing signal for providing as a final output signal only one of said filter output signals changeable to the other only

when both filter output signals are substantially in phase.

14. In an information transmission system for conveying selected binary bits spaced in time by a bit period, frequency-shift keying apparatus comprising, a source of a timing frequency signal having selected periodically spaced polarity reversals whose period is said bit period, a source of Zero and One fixed frequency signals respectively characteristic of the binary digits Zero and One, each frequency thereof and the frequency difference therebetween being integral multiples of said timing frequency, a mixer for combining said Zero and One signals to provide a difference frequency signal, a phase detector for comparing the phase of said difference frequency signal with said timing frequency signal to provide a phasing signal, phase control means energized by said phasing signal for constraining the phase difference between said One and Zero signals to be substantially zero coincidentally with said selected periodically-spaced polarity reversals, and means for selecting the fixed frequency signals characteristic of the selected bit to be conveyed and changing therebetween only coincident with a selected polarity reversal.

15. Frequency shift keying apparatus comprising, a source of a stable fixed frequency signal, a plurality of serially connected flip-flops for dividing said stable signal into a high frequency square wave signal which has leading and trailing polarity reversals during each period thereof, a second plurality of serially connected flip-flops set and reset by a polarity reversal of the preceding stage, the first stage being set and reset by said leading polarity reversals, thereby dividing said high frequency square wave signal into a plurality of lower frequency square wave signals, means for dividing said high frequency square wave signal to provide an odd square wave signal whose frequency is an odd submultiple of that of said first square wave signal, a third plurality of flip-flops for dividing said odd square wave signal to provide a timing square wave signal which has selected polarity reversals alternating with unselected polarity reversals, the time interval between alternate polarity reversals defining a bit period, a phasing flip-flop set by said selected polarity reversal and reset by said trailing polarity reversal of said first square wave signal which when reset provides a phase correcting signal for resetting said second plurality of flip-flops thereby providing a plurality of square wave signals whose polarity reversals which coincide with said selected polarity reversals are of the same sense, means for combining pluralities of said square wave signals to provide a pair of first and second fixed frequency signals the frequency difference therebetween being equal to said timing frequency, first and second filters energized by said pair for providing said first and second fixed frequency signals respectively as an output, a mixer which combines said first and second fixed frequency signals to derive a difference frequency signal, a phase comparator for comparing the phase of said timing signal with said difference frequency signal to derive a phasing signal, means for varying the phase shift characteristic of said first filter to maintain substantially no relative phase difference between said first and second fixed frequency signals coincident with said selected polarity reversals, a source of a reference signal, an amplitude comparator for each filter for comparing the output signal amplitude with said reference signal to provide a gain control signal, means for applying said gain control signal to an associated filter thereby maintaining the amplitude of each filter output signal at substantially the same constant level, and switching means which selects said first or second fixed frequency signal as an

output and changes therebetween only coincident with a selected polarity reversal to provide effectively a frequency shifted signal substantially free from undesired switching-induced amplitude variations.

16. In a multi-channel frequency shift keying system, apparatus comprising, a source of fixed frequency signals, a pair of mixers, each energized by said source of fixed frequency signals and having a set of output terminals, a filter associated with each mixer having an input terminal set, an output terminal set, a phase control terminal set, and an amplitude control terminal set, means for coupling the output terminal set of a mixer to the input terminal set of the associated filter, automatic gain control means having an output terminal set, 10 an input terminal set and an amplitude reference terminal set associated with each filter, a source of an amplitude reference signal, means for coupling said source of amplitude reference signal to said amplitude reference input terminal set, means for coupling the output terminal set of said automatic gain control means to said amplitude control terminal set, means for coupling the output terminal set of said filter to the input terminal set of said automatic gain control means, a final mixer with an input terminal set coupled to the output terminal set of each filter and having an output terminal set, a source of a timing signal having selected polarity reversals alternating with unselected polarity reversals, a phase detector with one set of input terminals coupled to the output terminal set of said final mixer, the other 20 input terminal set coupled to said source of a timing signal, and its output terminal set coupled to the phase control terminal input set of one of said filters, an output terminal set, and switching means which couples said output terminal set to one of said filter output terminal sets and changes to the other only in synchronism with said selected polarity reversals.

17. In a signalling system apparatus comprising, a source of a plurality of fixed frequency signals, means for providing a first of said fixed frequency signals as 25 an output signal, means for deriving a signal indicative of the phase relation between said first signal and a second of said fixed frequency signals, and switching means responsive to the phase indicative signal for changing the output signal to said second fixed frequency signal only when said first and second signals are substantially in phase.

18. Signalling apparatus comprising, a source of a plurality of fixed frequency signals and a timing signal, and switching means which provides a first of said fixed 30 frequency signals as an output signal and is operable in response to said timing signal for selectively substituting a second of said fixed frequency signals as an output only when said first and second signals are substantially in phase.

19. Frequency shift keying apparatus comprising a source of a timing signal and two fixed frequency signals, means responsive to said timing signal for effecting substantially zero phase difference between said two fixed frequency signals coincident with selected portions of said timing signal, and selective switching means operable in response to said timing signal for providing only one of said fixed frequency signals as an output signal which is changed to the other only coincident with said timing signal selected portions.
